US0D1088382S

(12) **United States Design Patent** (10) **Patent No.:** **US D1,088,382 S**
(45) **Date of Patent:** **** Aug. 12, 2025**

(54) **GUTTER CLEANER**

(71) Applicant: **GMOLAH, Inc**, Lathrup Village, MI
(US)

(72) Inventor: **Derek Thompson**, Lathrup Village, MI
(US)

(73) Assignee: **GMOLAH, Inc**

(**) Term: **15 Years**

(21) Appl. No.: **29/893,696**

(22) Filed: **Jun. 1, 2023**

(51) LOC (15) Cl. **07-05**

(52) U.S. Cl.

USPC **D32/35**

(58) **Field of Classification Search**

USPC D8/2; D32/15, 17, 25, 30, 35

CPC E04H 4/1627

See application file for complete search history.
